US00D812340S

(12) **United States Design Patent** (10) **Patent No.:** **US D812,340 S**
(45) **Date of Patent:** **** Mar. 13, 2018**

(54) **FOOD PRODUCT**

(71) Applicant: **Mars, Incorporated**, McLean, VA (US)

DE 4315124 11/1994
IT 000269 11/1997

(72) Inventor: **Vincent Joseph Falcone**, Inverness, IL (US)

(73) Assignee: **Mars, Incorporated**, McLean, VA (US)

(**) Term: **15 Years**

(21) Appl. No.: **29/569,856**

(22) Filed: **Jun. 30, 2016**

(51) LOC (11) Cl. **01-01**

(52) U.S. Cl.

USPC **D1/199**

(58) **Field of Classification Search**

USPC D1/100-130, 199; 426/5, 76, 87, 92, 94, 426/95, 99, 101, 103, 108, 138-139, 143, 426/144, 279, 282, 283, 391, 514, 549, 426/660; D13/100; D24/101-104; D28/8.1; 424/467; 425/195; 34/296; D6/601; D9/453

CPC .. A61K 9/2072; A61K 9/0004; A61K 9/2095; A61K 9/209

CLAIM

The ornamental design for a food product, as shown and described.

DESCRIPTION

FIG. 1 is a perspective view of a food product showing my new design;

FIG. 2 is a front view of the food product shown in FIG. 1; FIG. 3 is a rear view of the food product shown in FIG. 1; FIG. 4 is a left side view of the food product shown in FIG. 1;

FIG. 5 is a right side view of the food product shown in FIG. 1;

FIG. 6 is a top view of the food product shown in FIG. 1; and,

FIG. 7 is a bottom view of the food product shown in FIG. 1.

The broken lines shown in FIGS. 1-7 illustrate portions of the food product that form no part of the claimed design.

1 Claim, 7 Drawing Sheets
